(57) **CLAIM**

The ornamental design for an accessory holder for knives, hand tools, and the like, as shown and described.

DESCRIPTION

FIG. 1 is a perspective view of an accessory holder for knives, hand tools, and the like according to my new design;

FIG. 2 is a front elevation view thereof;

FIG. 3 is a top plan view thereof;

FIG. 4 is another perspective view thereof taken along cross-section 4—4 of FIG. 2, the left side elevation, right side elevation, bottom plan, and rear elevation views are not shown and are not claimed;

FIG. 5 is a perspective view of another accessory holder for knives, hand tools, and the like according to my new design;

FIG. 6 is a front elevation view thereof;

FIG. 7 is a top plan view thereof; and,

FIG. 8 is another perspective view thereof taken along cross-section 8—8 of FIG. 6, the left side elevation, right side elevation, bottom plan, and rear elevation views are not shown and are not claimed.

The broken lines shown herein depict unclaimed environmental structure.
